US00D875116S

(12) **United States Design Patent** (10) Patent No.: **US D875,116 S**
 Bae et al. (45) Date of Patent: ** Feb. 11, 2020

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Hyo-Jin Bae**, Seoul (KR); **Jakyoung Lee**, Seoul (KR); **Hyunwoo Choi**, Seoul (KR); **Cheonhyun Park**, Seoul (KR); **Yeongwoong Yoo**, Ansan-si (KR); **Jaein Yoo**, Seoul (KR); **Yongkoo Lee**, Seoul (KR)

(73) Assignee: **SAMSUNG ELECTRONICS CO., LTD.**, Suwon-si (KR)

(**) Term: **15 Years**

(21) Appl. No.: **29/612,134**

(22) Filed: **Jul. 28, 2017**

(30) **Foreign Application Priority Data**

Feb. 22, 2017 (KR) 30-2017-0008421

(51) **LOC (12) Cl.** **14-04**

(52) **U.S. Cl.**

USPC **D14/486**

(57) **CLAIM**

The ornamental design for a display screen or portion thereof with graphical user interface, as shown and described.

DESCRIPTION

The FIGURE is a front view of a display screen or portion thereof with graphical user interface showing our new design.

The outer broken lines in the FIGURE depict a display screen or portion thereof and form no part of the claimed design, and the remaining broken lines in the FIGURE depict portions of the graphical user interface that form no part of the claimed design.
